CLOSURE CAP ELEMENT FEEDING APPARATUS

Eibe A. Wilckens, Baltimore, Md., assignor to Crown Cork & Seal Company, Inc., Baltimore, Md., a corporation of New York

Application January 6, 1949, Serial No. 69,516

12 Claims. (Cl. 113—114)

The present invention relates to closure cap assembling apparatus.

An object of the invention is to provide an apparatus for assembling closure cap shells and liners; for example, cork liners.

Another object of the invention is to provide mechanisms which will be highly efficient for feeding cap shells and liners to rotating dials.

Still another object of the invention is to provide a shell feeding mechanism of such construction that should any jamming of the shells occur, the jam will be quickly relieved without damage to the feeding mechanism or shells.

Another object of the invention is to provide a mechanism for controlling the feeding of liners or other cap components.

A further object of the invention is to provide a mechanism for controlling the feed of liners in accordance with the feeding of shells.

Another object is to provide a liner feeding device including means for insuring that superposed liners will not adhere to each other.

The invention is hereinafter illustrated in connection with an apparatus for placing paper or fiber liners in threaded cap shells. However, it will be understood that the invention may be used for assembling other types of shells and liners.

Other objects of the invention will be apparent from the following specification and drawings wherein:

Figure 1 is a plan view of the machine.

Figure 2 is a vertical section through a shell feeding mechanism taken on the line 2—2 of Figure 1, as well as the line 2—2 of Figure 4.

Figure 3 is a vertical section of the machine primarily taken on the return-angled line 3—3 of Figure 1, though the lower right-hand portion of Figure 3 is taken on the line 4—4 of Figure 1.

Figure 4 is an enlarged vertical section of the shell feeding mechanism, the view being taken on the line 4—4 of Figure 1.

Figure 5 is an elevation, with portions broken away, of the shell feeding chute.

Figure 6 is a top elevation of the shell feeding and assembly mechanisms of the machine, the shell feeding mechanism being shown in horizontal section on the line 6—6 of Figure 4 and the assembly mechanism being shown on line 6A—6A of Figure 7.

Figure 7 is a vertical section through the assembly mechanism.

Figure 8 is a horizontal sectional view showing the shell feeding and liner feeding mechanisms. The shell feeding mechanism is shown substantially on the line 8—8 of Figure 4 and the liner feeding mechanism is shown substantially on the line 8A—8A of Figure 3.

Figure 9 is a vertical section through the liner feeding mechanism on the line 9—9 of Figure 8, the liner

2

supply tube being shown in elevation, as seen from that line, and with parts broken away.

Figure 10 is a developed view showing the liner stack tube as viewed from the left of Figure 8 and with the liner feeding control device shown on the line 9—9 of Figure 8.

Figure 11 is a vertical section on the line 11—11 of Figure 8.

Figure 12 is a horizontal section of the liner feeding mechanism on the line 12—12 of Figure 9.

Figure 13 is a fragmentary view showing the liner feed control device in a different position from that illustrated in Figure 11.

Figure 14 is a fragmentary vertical section on the line 14—14 of Figure 11.

Figure 15 is a view similar to that of Figure 14 but showing the liner feed control device in another position.

Figure 16 is a detail section of the lower portion of the liner stack tube, the view being taken on the line 16—16 of Figure 18.

Figure 17 is a horizontal section on the line 17—17 of Figure 10.

Figure 18 is a vertical sectional view on the line 18—18 of Figure 17.

Figure 19 is a view looking toward the structure of Figure 18 from the right of the latter figure, and with a cam-engaging roll shown in vertical section.

Figures 20 to 23 illustrate details of the liner loosening mechanism.

Figure 24 is an elevation of the liner feeding trip cam.

Figure 25 is a plan view, with parts in vertical section, of the plunger supporting housing of the assembly mechanism. The view shows one plunger in section on the line 6A—6A of Figure 7.

Figure 26 is a vertical section of the assembly mechanism on the angled line 26—26 of Figure 1, with portions broken away.

Figure 27 is a horizontal section on the line 27—27 of Figure 2.

Figure 28 is a detail view showing the liner feeding dial in plan.

Figure 29 is a sectional view on the angled line 29—29 of Figure 28.

Figure 30 is a section on the line 30—30 of Figure 28, and

Figure 31 is a fragmentary view showing a leading or liner-engaging face of the liner feeding dial.

General construction and operation

The construction and operation of the embodiment of the invention disclosed herein may be generally described as follows:

At the right of Figures 1 and 2, and also in Figure 4, there is shown a shell feeding dial 10 rotatable in a counterclockwise direction with a disc 12 and above a stationary table 13. At the left of Figures 1 and 8 is also shown a liner feeding dial 14 rotatable counterclockwise above a stationary table 16. As best shown in Figure 8, the dials 10 and 14, rotating in the direction of the Figure 8 arrows, respectively deliver shells S and liners L to an assembly mechanism 18. As indicated in Figure 7, assembly mechanism 18 includes a lower and rotatable disc 20 upon which the shell feeding dial 10 deposits the shells S. Assembly mechanism 18 also includes an upper disc or flange 22 rotatable with disc 20 and to which the liner feeding dial 14 delivers the liners. The upper disc 22 is provided with a circumferential series of apertures 24 and liner feeding dial 14 positions the liners L upon disc 22 in alignment with these apertures so that the liners L may drop downwardly in the apertures as shown at the left of

70

Figure 7. Shell feeding dial 10 places shells S on lower disk 20 of the assembly mechanism below and in alignment with the apertures 24. A series of plungers 26 included in assembly mechanism 18 reciprocate in the apertures 24 to force the liners downwardly through the apertures and into the shells S as shown at the right of Figure 7. The assembled caps are stripped from the lower table 20 of the assembly mechanism 18 by a stripper plate 28 (Figures 1 and 6) and the caps then move from the machine through the outfeed guideway 30 of Figure 1.

With regard to the infeed of the shells, threaded shells S of the form indicated in Figure 2 move downwardly through the shell feeding chute 32 and are engaged by the shell feeding spider 34 which rotates in timed relation with the shell feeding dial 10.

The liners L to be assembled with the shells are supplied from a liner stack tube 36 shown in Figures 8 and 9. The liner feeding dial 14 rotates beneath the tube 36 and includes upstanding teeth 38 arranged at the outer ends of its arms 40. As indicated in Figure 10, as a tooth 38 rotates beneath the lower end of the stack 36, it will push the lowermost liner out of stack 36 so that the liner will then ride upon the stationary table 16 with the rotating dial.

As is best shown in Figure 8, a detector lever 41 pivoted at 42 to the stationary table 13 associated with the shell feeding dial 10 has one end 43 thereof arranged in the path of movement of shells with shell dial 10. As is hereinafter explained, whenever a pocket of shell feeding dial 10 fails to receive a shell from the shell feeding chute 32, a spring 44 shown at the lower right of Figure 3 will cause end 43 of lever 41 to swing inwardly with respect to dial 10 as indicated in Figure 8, thereby operating liner feeding control device 45 best shown in Figures 8 to 15 to raise the liner supply tube 36 and the stack of liners L sufficiently that the tooth 38 of liner feeding dial 14 which next passes beneath tube 36 will not engage the lowermost liner in the stack. The shell dial 10 and liner dial 14 are so related that the pocket of shell feeding dial 10 which fails to receive a shell and the pocket of liner feeding dial 14 which thereby receives no liner from stack 36 would normally respectively place shells and liners in alignment with the same plunger 26 of assembly dial 22. Therefore, when the detector lever 41 forming part of the liner feed controlling mechanism 45 operates as described above, neither a shell nor a liner will be positioned beneath one of the plungers 26 of assembly mechanism 18.

As is illustrated in Figures 10, 12 and 17 to 23, the liner supply tube 36 has a device 46 associated therewith and operated by rotation of a cam with the liner feeding dial 14 to strike or tap the opposite sides of tube 36 to separate liners L which have adhered to each other. Such adherence can occur because of the coating usually applied to the liners.

The construction and operation of each mechanism of the apparatus is hereinafter described in more detail.

Drive mechanism

The apparatus is driven by a motor 48 (Figure 1) through a speed reducer 49 (Figure 3) including a driving pulley 50. Pulley 50 drives a belt 51 which engages a pulley 52 fixed to a main drive shaft 53 journaled in the base table 54 of the machine. Referring to Figures 7 and 27, a pinion 55 fixed to the upper end of shaft 53 meshes with a pinion 56 secured to a tubular shaft 57 journaled upon a stationary post 58 secured to the base table 54. As appears in Figure 7, the tubular shaft 57 has the assembly mechanism discs 20 and 22 secured thereto, as well as a turret 59 which serves as a carrier and guide for the assembly plungers 26. The position of the plungers is controlled by a stationary

cam generally designated 60 fixed to post 58. Cam 60, together with springs associated with the respective plungers 26, causes the plungers to vertically reciprocate during rotation of the assembly mechanism 18 and its plunger turret 59.

As is best shown in Figures 3 and 27, a gear 65 secured to a second tubular shaft 66 meshes with the assembly mechanism gear 56.

Shaft 66 is journaled upon a post 67 secured to the base table 54 and shell feeding dial 10 is secured to shaft 66. As a result, the shell feeding mechanism is driven from the assembly mechanism. A gear 70 forming part of the liner feeding mechanism also meshes with the assembly mechanism gear 56 and is secured to a hollow shaft 71 rotatable about a post 72 fixed to base table 54. The liner feeding dial 14 is secured to the tubular shaft 71 and is thereby also driven from the assembly mechanism.

20

Shell feeding

As is indicated in Figure 2, the shells S, usually of the type including threaded skirts, are delivered to the chute 32 through a suitable upper chute 75. The chute 32 is illustrated in Figures 1 to 3, 5 and 6, and includes an inner wall 76, edge walls 77 and 78 and a pivoted rear wall or plate 79. The front wall 76 is secured to a bracket 80 mounted on a casting or housing 81 fixed to the upper portion of post 67.

As is best indicated in Figure 2, an arcuate plate 83 including edge walls 84 extends from the lower end of the front plate 76 of chute 32 downwardly to a point adjacent the shell feeding dial 10. The inner wall 76 terminates adjacent the upper end of the arcuate plate 83 and the lower portion of wall 76 is cut away or slotted as indicated at 85 in Figure 5. As the shells descend in chute 32 they successively come into contact with stop arms 86 and 87 which are respectively pivoted on pins 88 and 89 extending horizontally of the chute. As appears in Figure 5, the lower ends of the stop arms 86 and 87 are bent inwardly to project into the path of shells dropping in the chute. As a result, the lowermost cap in the straight portion of chute 32 will rest upon the in-turned ends of the stop arms until engaged by the spider 34. The arms 86 and 87 are urged toward each other by a spring 90 connected to pins fixed to the arms, the inward movement of the stop arms being limited by adjustable set screws designated 91. The tension exerted by spring 90 is sufficient to support all of the caps which may be above the stop arms but will permit the lowermost cap to be drawn past the stop arms by the spider 34.

The shell feeding spider 34 has radially extending pins 34a circumferentially spaced about its periphery, the spacing being slightly greater than the overall diameter of the shells being handled, and the pins 34a extend through the slot 85 of wall 76 to engage the lowermost shell in chute 32 to move that shell down plate 83 to dial 10.

In order to prevent damage to the shells or shell feeding mechanism by any jamming of shells in chute 32, the chute rear wall 79 is fixed to a pin 92 which is rotatable in lugs 92a rigid with the front wall 76 of the chute. As best shown in Figure 5, rear wall 79 includes an out-turned flange 93 at its upper end which is secured to pin 92 by a set screw 93a. In order to hold the rear wall 79 in the normal position indicated in Figure 2, a torsion spring 94 is mounted on the pin 92, one end of the spring engaging a collar 95 fixed to the pin, while the opposite end of the spring is engaged in the adjacent pin supporting lug 92a. The inward movement of plate 79 is limited by a set screw 96 adapted to bear against the upper end of the arcuate plate 83 of chute 32. Torsion spring 94 exerts sufficient tension that the outer or rear wall 79 of the chute will normally be held in the position illustrated in Figure 2. However, should any jamming of shells 75 occur, so that one shell tends to override another, spring

94 will permit the rear wall 79 to swing outwardly so that the jam will be relieved.

The lower and curved portion 83 of chute 32 is curved on an arc concentric with spider 32, the inner surface of the plate being only slightly spaced beyond the ends of the spider pins 34a.

As is best shown in Figure 6, the spider 34 is fixed to a sleeve 98 which is journaled on a pin 99 fixed in the housing 81 and extends radially of post 67. Sleeve 98 is provided at its inner end with beveled gear teeth which engage an upwardly facing beveled gear 100 fixed to the rotating sleeve 66 of the shell feeding dial 10. As a result, the shell feeding spider 34 and the shell feeding dial 10 will rotate in synchronism so that each shell which moves downwardly with spider 34 will be engaged by one of the pockets 101 of dial 10.

As is shown at the right of Figure 3 and also in Figure 8, the dial 10 is circumferentially adjustable relative to the sleeve 66 so that the position of the dial pockets 101 with respect to the shell feeding device 32 and the assembly 15 mechanism 18 can be adjusted.

The liner feeding means

Figures 8 to 16 disclose the arrangement included in the present invention whereby liners or other cap elements may be fed under the control of a detector means such as 41.

As is best shown in Figures 11 and 12, the liner feed control device 45 includes a collar 105 fixed to the stationary post 72 of the liner feeding mechanism. Sleeve 105 has a radially extending housing 106 formed integrally therewith, the housing extending radially above the liner feeding dial 14. Housing 106 includes an aperture 107 at its outer end, and collar 105 includes an aperture 108 aligned with aperture 107. A tubular or sleeve element 109 has its opposite ends journaled in the apertures or bores 107 and 108 so that sleeve 109 will be rotatable about an axis extending radially of the liner feeding dial 14. A spring pressed pin 110 has its inner end lying within an annular groove 111 of sleeve 109 to prevent the latter from moving radially of the dial 14 or along its own axis.

Adjacent its inner end, sleeve element 109 is squared as best indicated in Figure 14 to thereby provide four flat surfaces 112 at 90° to each other, the adjoining ends of the surfaces 112 thereby forming what may be regarded as apices 113. As is hereinafter described, the flats 112 and splices 113 respectively comprise the dwells and rises of a cam generally designated 114. Hence, sleeve 109 may be termed a cam sleeve. A rod 115 is slidable axially of the sleeve element 109, the inner end of the rod being seated within a bore 115a of the sleeve. At its outer end, rod 115 has a swivel connection to the forked end of detector lever 41 as is best shown in Figure 8.

A second or cam actuator sleeve 116 is fitted on the exterior of the cam sleeve 109, and sleeve 116 is rigidly secured to the rod 115 by means of a cotter pin 117 which extends through and closely fits a small aperture in the rod and aligned small apertures in sleeve 116. Cotter pin 117 also extends through a slot 118 in cam sleeve 109, this slot being enlarged axially of sleeve 109 so that the cotter pin will be free to move axially of cam sleeve 109 with rod 115 and cam actuator sleeve 116. Cotter pin 117 also serves as a means to connect sleeve 109, rod 115 and cam actuator sleeve 116 for rotation about the axis of sleeve 109. For this same purpose, a key 116a on sleeve 116 engages a keyway 109a in sleeve 109.

As is best shown in Figure 10, at its inner end the cam actuating sleeve 116 is provided with two circumferential series of trips or teeth respectively designated 120 and 121. As appears in Figures 12 and 13, these two series of trips are spaced axially of sleeve 116, and series 120 is outermost on sleeve 109. Each series includes four radially projecting teeth, the teeth of one series being circumferentially alternate with the teeth of the other series.

Referring to Figure 11, a collar 125 is reciprocable of the stationary post 72. As is shown in Figure 9, the liner stack tube 36 is rigidly secured adjacent its lower end to collar 125. As is indicated in Figure 3, a second or upper collar 125a rigid with the upper portion of liner stack tube 36 is also vertically slidable upon post 72. A cam follower plate 126 is adjustably secured to collar 125 in vertical alignment with the cam 114.

As is indicated in Figure 11, a spring 125b positioned 10 on post 72 between collar 125a and a rigid collar at the top of the post may be used to urge the collars 125 and 125a and tube 36 to their lowered position on the post.

As shown in Figures 9, 18 and 19, the lower end of liner supply tube 36 includes two inwardly projecting bottom flanges or walls 130 and 131 and, as best appears in Figure 12, these flanges are spaced apart so that diametrically opposite areas of the lowermost liner in the stack may rest thereon. Flange 131 may include slight rises 131a at its ends to prevent liners from adhering too closely to it. The two flanges are spaced sufficiently far apart to permit the upstanding teeth 38 of liner feeding dial 14 to move between them. The height of a tooth 38 with respect to the liner supply tube 36 is best indicated in Figure 9 from which it will be perceived that when the tube is in the lowered position illustrated in that figure, the teeth 38 may move through a slot 133 at the entrance side of tube 36 (the left-hand side in Figure 10) and outwardly through an opening 134 on the exit side of the tube, each tooth 38 having sufficient height that it will engage only the lowermost liner in the stack as indicated in Figure 10 to withdraw that liner below a stop 135 mounted at the exit side of tube 36. The opening 134 at the exit side of the tube obviously will be of sufficient extent circumferentially of the tube to permit a liner to move freely therethrough. Stop 135 is vertically adjustable with respect to tube 36 by means of the slot and set screw arrangement designated 136 and illustrated in Figure 9.

It will be noted from Figure 9 that when the tube 40 36 is in the lowered position illustrated in that figure, the under surface of the bottom flange 131 of the tube will be in close contact with the upper surface of liner feeding spider 14. However, a sufficient clearance will exist at this point and also between the lower end of stop 135 45 and the upper surface of the dial tooth 38 to enable the dial to rotate freely beneath the stack tube 36.

As is best shown in Figures 9 and 28 to 31, the hub of liner feeding dial 14 is provided with a circumferential series of slots 140 opening into an annular recess 141 in the upper surface of the hub. Set screws 142 extending through the slots 140 and having their heads lying within recess 141 serve to hold the dial 14 in circumferentially adjusted position upon the rotatable tubular shaft 71 of the liner feeding mechanism. As appears in Figure 9, a ring 145 is fixed to the hub portion of dial 14 by means of set screws 146 threaded in sockets 147 (Figure 28) circumferentially spaced about the recess 141 of dial 14.

A circumferential series of pins 148 extend upwardly from the ring 145, the pins 148 corresponding in number 60 with the number of teeth 38 provided on dial 14. As is hereinafter described, the pins 148 are adapted to contact one or the other of the series of cam actuating teeth or trips 120 or 121 fixed to cam actuator sleeve 116. Hence, the pins 148 may be regarded as strikers. Figures 17 and 24 show a modified form of ring including strikers consisting of teeth 148a formed integrally with a ring element 145a, the element 145a also including a cam structure adapted to cooperate with the device 46 which prevents liners from adhering to each other. Ring 145a would be adjustably secured to the hub of dial 14 by means of slots and set screws 146.

The operation of the liner feed control mechanism 45 is as follows: So long as each pocket of the shell feeding dial 10 receives a shell S from the shell feeding spider 75 34 and chute 32, the outer end 43 of the detector lever

41 will be held outwardly or to the right of the position shown in Figure 8 by reason of the resultant movement of shells past the position indicated in dotted lines at A in Figure 8. Under these circumstances, the cam follower 126 fixed to the guide sleeve 125 of liner stack 36 will bear upon one of the flats or dwells 112 of cam 114, and the stack 36 will be in the lowered position shown in Figure 9. Therefore, each tooth 38 of liner feeding dial 14 will successively remove a liner L from the lower end of tube 36.

In the event that a pocket of shell feeding dial 10 moves past the position approximated at A in Figure 8 and without a shell S therein, the spring 44 of Figure 3 urges the outer end of detector lever 41 in the direction of arrow A1 to the inward position illustrated in Figure 8. Therefore, the left-hand end of lever 41 will move in a direction opposite to that indicated by the arrow A2 in Figure 8, thereby forcing the rod 115 and cam actuating sleeve 116 in the same direction, viz., outwardly. This will cause the inner series of trips 121 to be positioned in the path of movement of the strikers or pins 148. As a result, the next striker 148 which moves beneath the cam actuating mechanism will have one of the inner series of trips 121 extending vertically downwardly in its path as shown in Figures 9 and 10. The striker 148 will contact with this trip and thereby rotate cam actuator sleeve 116 through approximately 45° so that no trip of the inner series 121 will project into the path of the strikers 148. A trip of the outer series 120 will now project downwardly but at the moment this series of trips is radially outwardly of the path of movement of the strikers 148.

As the result of the above mentioned rotation of the cam actuator sleeve 116 and cam sleeve 109, the latter will rotate from the position illustrated in Figure 14 to that illustrated in Figure 15. Hence, an apex or rise 113 of cam 114 will rotate beneath the cam follower 126, thereby lifting cam follower 126 from the Figure 14 position to that shown in Figure 15 and also lifting the stack tube 36. The stack tube 36 will rise sufficiently that the lowermost liner therein will be positioned above and clear of the upper surface of the liner dial teeth 38. Hence, the next tooth 38 which passes beneath the stack tube cannot remove a liner from the stack. It will be understood that the dials 10 and 14 will be so synchronized that the tooth 38 just described as failing to remove a liner would ordinarily remove a liner for assembly with the shell of the pocket of shell dial 10 which has been described as failing to receive a shell. Also, a striker 148 of liner dial 14 will be positioned about 90° in advance of the tooth 38 with which it is associated, the spacing primarily depending upon the distance by which the liner feed controlling device 45 is positioned in advance of liner tube 36.

If a series of pockets of shell feeding dial 10 fail to receive a shell after the liner feed tube has been raised, the stack 36 will remain in elevated position due to the fact that the inner series of trips 121 remain aligned with the path of the corresponding series of strikers 148. Because the teeth of series 121 are clear of the strikers, the latter will simply pass beneath trips 121 without rotating the cam actuator sleeve 116 or the cam sleeve 109. However, as soon as a pocket of shell feeding dial 10 receives a shell S from the shell feeding chute 32, the movement of that shell past position A of Figure 8 will cause the right-hand end of the detector lever 41 to be swung outwardly from the position illustrated in Figure 8. As a result, the left-hand end of lever 41 will move inwardly in the direction of arrow A2 to thereby position the outer series of trips 120 in alignment with the strikers 148. Because one of these teeth will be projecting downwardly, the next striker 148 which passes below device 45 will rotate the cam actuator sleeve 116 and the cam sleeve 109 so that cam 114 will be rotated from the position shown in Figure 15 to the position shown in Figure 14.

In other words, the rise or apex 113 of the cam which has been supporting the cam follower 126 will be moved from beneath the cam follower and a dwell or flat 112 will move beneath the cam follower. Therefore, the cam follower 126, sleeve 125 and liner stack tube 36 will drop to the lowered position illustrated in Figures 9 and 10 so that the next tooth 38 which moves beneath the stack tube 36 will remove the lowermost liner from the stack.

10

Liner loosening mechanism

When the cap elements handled by the stack tube 36 are disc-type liners coated with wax, they tend to adhere to each other in surface to surface contact. As a result of this adherence, when a tooth 38 of the liner feeding dial 14 strikes the lowermost liner L, that liner may be marred because it is not free to move away from the upper and next adjacent liner. The present invention includes an arrangement to so agitate the stack tube and liners that any tendency of the liners to adhere to each other will be overcome.

The arrangement just referred to is best illustrated in Figures 17 to 24. Referring first to Figures 17 and 24, a ring cam 160, preferably formed as part of the striker ring 145a, is positioned above the hub of the liner feeding dial 14 as indicated in Figure 11. The cam 160 includes alternate rises 161 and relatively slight dwells 162. The surface of the cam is vertically tapered in order that correspondingly tapered cam engaging rollers hereinafter described may cooperate therewith.

As is best shown in Figures 9 and 19, the liner stack tube 36 has a bracket 165 secured to its lower end and on its surface nearest the fixed post 72. A vertical pin 166 is journaled in a vertical bore 166a of bracket 165 and at its lower end journal pin 166 has a bar 167 fixed thereto, the plate extending in opposite directions from the pin. At each end, bar 167 carries a roller 168 suitably rotatable on a vertical axis such as the headed pin 169, shown in Figure 19. As is also shown in Figure 18, the lower end of each roller 168 is tapered as indicated at 170, this taper being complementary to the taper of the surface of cam 160. Journal pin 166 has a substantially U-shaped plate 171 fixed to its upper end as indicated in Figures 20 and 21 and also in Figure 17. As 45 appears in the latter figure, the plate 171 partially surrounds the stack tube 36.

The outer ends of plate 171 have flat fittings 172 welded thereto and which fittings lie in parallel vertical planes. Each fitting 172 has a relatively large set screw 173 threaded therethrough, these set screws being so positioned with respect to the stack that they lie on a line extending diametrically through the stack tube 36.

Stack tube 36 has a diametrically opposite apertures 174 formed therein, and, as shown in Figure 17, the inner ends of the set screws 173 extend into these apertures though the inner ends of the set screws will be separated by a distance somewhat greater than the diameter of the liners L. Each fitting 172 carries a small set screw 175 which is adapted to contact with the outer surface of stack tube 36 at a point slightly below the corresponding aperture 174. The set screws 175 will limit the inward movement of the upper set screws radially of the stack tube and also exert a slight tapping effect upon the stack tube wall.

In operation, as cam 160 rotates with the liner feeding dial 14, the engagement of the liners 168 with the cam will cause the bar 167 and plate 171 to be oscillated about the vertical axis of the journal pin 166. Cam 160 will be so designed with respect to the spacing apart of the rollers 168 that as a rise 161 moves under one roller, a dwell 162 will be moving beneath the other roller.

The above-mentioned oscillation of plate 171 will cause the opposite ends of the pins 173 to oscillate or alternately move through the opposed apertures 174 in the stack tube. The range of oscillation is sufficient that

75

as a liner moves downwardly in the stack to bring its perimeter into the path of the set screws or tappers 173 it will be laterally separated from the liner immediately above by reason of radial movement imparted to it by the set screws 173.

In order that the liners in the path of the tapper may have radial movement with respect to the liners above and below the path of the tappers, the inner surface of the stack tube 36 is recessed in the plane of the tappers as indicated at 180 in Figures 17 and 18. It will be observed that two recesses 180 are provided, each recess extending through about 90° on each side of each aperture 174. The recesses 180 have their greatest depth adjacent the apertures and are of gradually decreasing depth to a diametric line lying midway between the apertures. The extent of the recess in a vertical plane substantially corresponds to the diameter of the pins 173.

The effect of the above-mentioned recesses 180 is to provide a space within the tube 36 into which the liners L may be radially moved in the direction of tapping movement of the tappers 173. It will be noted that the upper and lower edges of the recesses are rounded to avoid any sharp shoulders upon which the liners might lodge when they are radially offset by the action of the tappers. The recesses need only be very shallow in a radial direction to provide sufficient space for the offsetting or loosening action of the tappers 173.

Assembly mechanism

As is best illustrated in Figure 8, the rotation of the shell feeding dial 19 in a counterclockwise direction will cause the shell to be moved toward the assembly mechanism 18 and rotation of the liner feeding dial in the same direction will move the liners L to the assembly mechanism. The shells are guided to the lower table 20 of the assembly mechanism by a guide strip 185. The pockets of shell feeding dial 19 move in synchronism with the bores 24 of the upper plate 22 of the assembly mechanism so that each shell will be placed below a bore 24. At that instant, the plunger 26 associated with the bore will be in a raised position. Rotation of the assembly mechanism 18 in synchronism with the liner feeding dial 14 will bring the bore 24 to the point illustrated in Figure 8 at which a liner will be placed in the upper end of the bore 24.

The shells will be prevented from moving radially out of alignment with the bores 24 by an arcuate guide strip 186 extending about the lower table 20 of the assembly mechanism beyond the point of infeed of the shells. In order to prevent the shells from sliding circumferentially of the table 20, the latter is provided (Figure 7) with upwardly projecting pins 188, one in advance of and one behind each bore 24, the pins being spaced circumferentially of table 20 by a distance substantially corresponding to the outside diameter of a shell S.

The assembly mechanism plungers 26 are best illustrated in Figures 6, 7, 25 and 26. Referring to those figures, it will be observed that the turret 59 which carries the plungers 26 is secured to the tables 20 and 22 by means of removable pins, the turret including a lower sleeve portion 190 which surrounds the upper end of the tubular shaft 57. The upper portion of turret 59 includes radially projecting hollow box-like bosses 191 each of which serves as a guide housing for a plunger assembly. Each boss includes a lower horizontal wall 192, side or radial walls 193, and a top wall 194. The radially outward wall 195 of the boss is slotted as indicated at 196, this slot serving as a guideway for a roller as hereinafter described. The inner side of each boss 191 is open so that a roller associated with the plunger 26 may extend from the boss to engage the cam 60.

Each plunger device comprises a sleeve 198 which is vertically reciprocable through a bore 199 in the lower wall of the corresponding housing 191. Sleeve 198 is of reduced diameter at its upper portion so as to provide an

upwardly facing shoulder 200 approximately midway of the length of the sleeve. A collar 201 bears upon the shoulder 200, this collar including two radially projecting pins 202 and 203 which extend in opposite directions. As indicated in Figure 6, collar 201 may be of rectangular outline in plan. The inwardly projecting pin 203 has a roller 204 journaled thereon adapted to engage the cam 60, and the outer pin 202 has a second roller 205 journaled thereon which roller engages the edges of the slot 196 in the outer wall 195 of boss 191. Collar 201 is held down upon shoulder 200 by means of a second sleeve 206 having its upper end engaged by a nut element 207 threaded on the upper end of sleeve 198.

The stem 209 of plunger 26 is vertically movable within the bore 210 of sleeve 198. The upper portion 211 of stem 209 is of reduced diameter to provide an upwardly facing shoulder against which the lower end of a coil spring 212 may bear. The upper end of spring 212 engages a downwardly projecting shoulder at the upper end of sleeve 198. The upper stem portion 211 extends through an end aperture 213 in sleeve 198 and a nut 214 is threaded on the stem above the sleeve, nut 214 normally being urged into contact with the upper end of the sleeve by the action of spring 212.

Cam 60 is of drum-type and formed of two flanged discs 220 and 221. Disc 220 is fixed to a collar 222 rigid with the stationary post 58 and includes an upwardly extending flange 223 concentric with the axis of the post. The upper disc 221 extends a downwardly projecting flange 224, both flanges having the same radius. The vertically facing edges of the flanges are suitably contoured to cause the plungers 26 to be vertically reciprocated as the plungers move about the cam. The space between the opposed edges of the flanges 223 and 224 is such that the cam engaging rollers 204 of the plungers 26 will closely contact both edges.

The plunger and cam structure described above insures that the vertical movement of the plunger sleeves 198 will be closely controlled. The fact that each plunger includes a cam engaging roller 204 and a diametrically opposite guide roller 205 permits each plunger to be moved vertically without possibility of any rotation about its axis such as would twist the cam engaging roller 204 out of a proper radial relationship with the cam 60. Although each plunger sleeve 198 has its movement rigidly controlled by cam 60, the provision of the spring 212 upon the plunger stem enables plunger 26 to resiliently engage a liner L to move it downwardly through the bores 24 and into a cap shell S.

It will be understood that the cam 60 is of such design that a plunger 26 will rise to extreme elevated position at approximately the instant it reaches the position designated U in Figure 1, viz., an instant before the assembled shell and liner engage stripper 28 of outfeed guideway 30 for removal from the machine. The plunger will remain in lifted position until approximately the position designated D in Figure 1, by which time a liner L will have been placed in the upper end of the bore 24 corresponding to that plunger. The plunger will then descend to move the liner L downwardly into the shell S to thereby assemble the shell and liner. The plunger will remain in lowered position until position U of Figure 1 is again reached.

The terminology used in the specification is for the purpose of description and not of limitation, the scope of the invention being defined in the claims.

I claim:

1. In a cap assembling apparatus, a base, a vertical guideway fixed to said base, a dial rotatable with respect to said base and including a circumferential series of pockets, a cap element supply tube positioned above said dial and supported on said guideway for vertical movement, a circumferential series of strikers rotatable with said dial, a cam supported by said base for rotation about a horizontal axis and including a rise and a dwell, a cam

follower fixed to said supply tube and engaging said cam, a cam actuator rotatable with respect to said cam and including two circumferential series of trips, the two series of trips being spaced axially of said actuator and the trips of the respective series being circumferentially staggered, said cam actuator being movable axially of said cam so that said series of trips will be selectively positionable in the path of movement of said strikers, and means to control the position of said cam actuator with respect to said strikers.

2. A cap assembling apparatus of the character defined in claim 1 including a second dial, means to feed another cap element to said second dial, and wherein the means to control the position of said cam actuator comprises a detector responsive to the feed of the last-mentioned cap elements.

3. In combination, a base, a cap element supply tube carried by said base, said tube including a lateral opening, an oscillatable tapping element pivoted on said base and including a blunt portion movable into the tube opening to radially engage the edges of cap elements within the tube, and a second portion adapted to strike the outside of said tube.

4. The combination described in claim 3 including a tapping element oscillating cam which is rotatable on said base about an axis parallel with the pivotal axis of said tapper.

5. The combination described in claim 3 wherein the inside surface of the tube bore is recessed opposite the tube opening so that the tapping element may move a cap element radially into the wall recess.

6. In combination, a base, a cap element supply tube including diametrically opposite openings in its wall, a tapping element pivoted on said base on an axis parallel with the axis of said tube and including two arms, one extending adjacent each of the tube openings, a pin on each of the respective tapping element arms and extending substantially radially of the tube in alignment with the tube openings, both of said pins lying in the same plane and each including a blunt cap engaging end, and means to move said pin ends alternately into the tube openings.

7. The combination described in claim 6 wherein diametrically opposite portions of the inside surface of the tube bore are recessed, each recess extending over an area approximately 180° in extent, the respective tube openings being positioned at the median and deepest point of a recess.

8. In combination, a base, a cap element supply tube carried by said base, a cap element conveying means supported and movable on said base below said tube to receive cap elements therefrom, a tapping element pivoted on said base on an axis parallel with the axis of said tube, said tapping element including a pair of striker arms extending on opposite sides of said tube, and means operatively engaging said tapping element and movable with said cap conveying means to oscillate said tapping element and move said striker arms alternately toward and away from said tube to strike the latter and thereby agitate the stack of cap elements in said tube.

9. In a cap handling apparatus, a base, a cap element conveying means movable in a predetermined plane with respect to said base, means to move said cap element conveying means in said plane, a cap element supply device, means to move said cap element supply device in a direction normal to said plane from a first position to a second position, and means carried by said cap element conveying means and movable in a path determined by said plane, said last mentioned means being adapted to successively engage and remove cap elements from said cap element supply device when the latter is in said first position, said last mentioned means being inoperative to remove cap elements from said cap element supply device when the latter is in said second position.

10. In a cap handling apparatus, a base, a cap element conveying means movable in a predetermined plane with

respect to said base, means to move said cap element conveying means in said plane, a cap element supply device, means to move said cap element supply device with respect to said base along a line at an angle to the plane of movement of said cap element conveying means from a first position to a second position, and means on said cap element conveying means operable in a path determined by said plane, said last mentioned means being adapted to engage and successively remove cap elements from said cap element supply device when the latter is in said first position and being inoperative to remove cap elements from said cap element supply device when the latter is moved to said second position.

11. In a cap handling apparatus, a base, a cap element conveying means movable with respect to said base in a substantially horizontal plane, means to move said cap element conveying means, a cap element supply device on said base above said cap element conveying means, means to move said cap element supply device vertically from a first position to a second position, and means carried by said cap element conveying means and movable in a path determined by said plane, said last mentioned means being adapted to successively engage and remove cap elements from the lower portion of said cap element supply device when the latter is in said first position, and said last mentioned means being inoperative to remove cap elements from the lower portion of said cap element supply device when the latter is in said second position.

12. In a cap assembly apparatus, a base, a cap element conveying means movable with respect to said base, means to move said cap element conveying means, a first cap element supply device, a second cap element supply device, at least said first cap element supply device being associated in feeding relation to and movable adjacent and away from said cap element conveying means, means operatively connected to said first cap element supply device to move it adjacent and away from said cap element conveying means, said cap element conveying means including means operative to engage and remove a cap element from said first cap element supply device when the latter is adjacent said cap element conveying means and inoperative to engage a cap element when said first supply device is away from said cap element conveying means, and means operatively connected to said first supply device moving means including a detector responsive to the feed of cap elements from said second supply device to control the position of said first supply device with respect to said cap element conveying means.
